UNITED STATES PATENT OFFICE.

REZSÖ BÉRES, OF KOBOLKUT, CZECHOSLOVAKIA.

AIRSCREW.

Application filed August 7, 1926, Serial No. 127,921, and in Hungary April 4, 1925.

This invention relates to auxiliary rotor devices for airscrews (propellers).

In airscrews having a high speed of rotation air is forced backwards between the 5 vanes or blades, at a considerable velocity in a direction opposite to the direction of travel. This air possesses a substantial amount of kinetic energy and it is the object of the present invention to utilize such 10 energy.

For the solution of this problem a blade wheel or rotor is mounted on the shaft of the air screw, to the rear of the latter, (having regard to the direction of travel) the blades 15 of said rotor being either straight or curved but, in either case, always parallel to the direction of travel. In other words, said blades must not form an angle with the direction of travel. This rotor is mounted on a hollow 20 shaft which, in turn, is mounted rotatably on the shaft of the airscrew and it is rotated by the current of air or slip stream forced back in an acute angle between the vanes or blades of the said screw.

25 In the accompanying drawing, which shows one constructional form of the auxiliary rotor device according to the invention,

Fig. 1 is a sectional side view of an airscrew and rotor, while

30 Fig. 2 is an end view thereof.

In this drawing the reference character *a* represents the airscrew, which may be provided with two or more vanes or blades, the latter being secured at their inner ends to 35 a drum shaped hub *h*, keyed to the screw shaft *b* and at their outer ends to a ring *f*. On the drum-shaped hub *h* is fastened a cone *e*, with its point directed outwards, which serves to reduce the air resistance.

40 In accordance with the invention an auxiliary blade wheel or rotor is mounted on the screw shaft *b* and this rotor is constructed in the following manner:

A hollow shaft *d* is mounted rotatably on 45 the screw shaft *b* behind the airscrew (having regard to the direction of travel) and upon the end thereof is fastened the drum-shaped hub *i*. This latter is equal in diameter

to the hub *h* and is arranged behind the same, with a small clearance. The inner ends 50 of the blades *c* are fastened to the hub *i*, while their outer ends are united by a ring *g*. The blades *c* may be straight or curved but whichever kind of surfaces is chosen, however, their generatrices must always be 55 parallel to the direction of travel. In order that the air may be properly guided and that no stray currents or eddies may be set up, it is desirable that the rings *f* and *g* mutually overlap. In the arrangement shown in 60 the drawing the ring *g* slightly overhangs the ring *f*.

In order to utilize the power obtained from the blade wheel *i*, *c*, *g*, any preferred form of transmission gearing arranged between the screw-shaft *b* and the hollow shaft *d* may be employed and by this means the power is taken off in any convenient manner, when it may be employed, for instance, 70 for supplementing the effect of the airscrew.

The auxiliary rotor device above described may, for example, be used with aircraft, watercraft or various other kinds of vehicles.

What I claim is:

1. In combination with an airscrew a rotor mounted rotatably on the shaft of the airscrew and to the rear of the latter, having regard to the direction of travel and provided with blades the generatrices of which are parallel to the direction of travel. 75

2. In combination with an airscrew a rotor mounted rotatably on the shaft of the airscrew and to the rear of the latter, having regard to the direction of travel and provided with straight blades the generatrices of 80 which are parallel to the direction of travel.

3. In combination with an airscrew a rotor mounted rotatably on the shaft of the airscrew and to the rear of the latter, having regard to the direction of travel and rings surrounding the airscrew and the rotor and arranged in mutually overlapping relation. 85

In testimony whereof I affix my signature.

REZSÖ BÉRES.
